UNITED STATES PATENT OFFICE.

ERNEST J. BURGQUIST, OF CHICAGO, ILLINOIS.

CHANGEABLE SIGN.

1,046,963.

Specification of Letters Patent.

Patented Dec. 10, 1912.

Application filed May 27, 1912. Serial No. 700,066.

To all whom it may concern:

Be it known that I, ERNEST J. BURGQUIST, a citizen of the United States, and resident of Chicago, county of Cook, and State 5 of Illinois, have invented certain new and useful Improvements in Changeable Signs, of which the following is a specification, and which are illustrated in the accompanying drawings, forming a part thereof.

10 The invention relates to signs, and more particularly to those adapted to be used for indicating the price of articles displayed for sale, and for similar purposes.

15 The object of the invention is to provide a sign for the purpose described having provision for changing certain of the characters thereof.

20 The invention contemplates a display card and a plurality of movable elements behind the card so mounted as to be capable of independent adjustment to display different characters upon the front of the card, and the whole device being of simple and compact construction.

25 In the accompanying drawings—Figure 1 is a front face view of a sign embodying the features of improvement provided by the invention; Fig. 2 is a rear face view of the same; Fig. 3 is a sectional view taken on the line 3—3 of Fig. 1; Fig. 4 is similar to Fig. 3, but shows the construction of a sign having a greater number of movable elements; Fig. 5 is a rear face view of the form of sign illustrated in Fig. 4; Fig. 6 30 is a detail front face view of a sign constructed in the manner illustrated in Figs. 4 and 5; and Fig. 7 is a front face view of one of the movable elements of the sign.

40 In carrying out the invention, a display card, as 10 or 11, is employed. Preferably this display card will have a sight aperture, as 12 or 13. The remainder of the face of the card 10 or 11 which is not cut away by the provision of the sight opening may be 45 employed for displaying printed information, as that shown at 14, Fig. 1. The changeable matter displayed by the sign will be preferably made up of characters displayed through the sight opening 12 or 13. Ordinarily this matter will consist of 50 but two characters, such as a price mark, indicated by the figures shown at 15 and 16, in Fig. 1. If desired, however, this changeable matter may be made up of a greater number of characters, as those shown at 17, 18, 19 and 20, Fig. 6.

The changeable characters, as those indicated at 15 and 16, Fig. 1, are preferably printed upon the marginal portions of rotatable disks, as 21, 22. The number of these 60 disks employed will usually be equal to the number of characters desired to be displayed through the sight opening 12 or 13. In the form of construction illustrated in Figs. 4, 5 and 6, four such disks are employed. In these figures, several disks are indicated by the numerals 23, 24, 25 and 26 respectively. All of the disks shown in the various figures of the drawings are of like construction. One of these, namely, the disk 70 21, of the structure illustrated in Figs. 1, 2 and 3, is illustrated as being separated from other parts in Fig. 7. A series of characters, of which the one 15 appearing through the sight opening 12 in Fig. 1 is 75 one, is printed about the marginal portion of the disk.

Compactness of construction is obtained by having the disks, as 21 and 22, overlap for the greater portion of their extent. In 80 order that the disks may be independently rotated, however, it is essential that they be separately pivoted. As shown in Figs. 1, 2 and 3, the disk 21 is pivotally mounted upon the card 10, as by means of the tubular rivet shown at 27. For supporting the disk 22 a member 28 is extended over the back of the card in rear of the disks. As shown, the member 28 takes the form of a strap which is equal in length to the length 85 of the card 10. This strap is secured to the card 10 adjacent its opposite ends, as by means of the rivets 29 and 30. The disk 22 is pivotally mounted upon the strap 28, as at 31, Figs. 2 and 3. The construction permits of the disks 21 and 22 being independently rotated, whereby either of the characters, as 15, 16, appearing through the sight opening 12 may be changed. A sign is thus provided which is adapted to be used for 90 indicating the price of articles displayed for sale, and that part of the sign material which indicates the price being changeable to accord with variations in the price of the article.

105 In the form of construction illustrated in Figs. 4, 5 and 6, the disk 23 is pivotally mounted upon the card 11, as at 32, Fig. 4. For supporting the disks 24, 25 and 26, a pair of straps, designated 33 and 34, are extended over the back of the card 11. Most conveniently these straps are arranged di- 110

agonally upon the back of the card and are inclined in opposite directions. They are preferably secured to the card 11, and for this purpose rivets, as 35, 36, are passed 5 through the straps 33, 34, respectively, adjacent their opposite ends and through the card 11. The strap 33 serves for supporting the disks 24 and 25. These disks are arranged upon opposite sides of the strap in 10 order that they may be independently rotated. They are pivotally secured to the strap, as by the rivets 37 and 38. The strap 34 serves for supporting the disk 26. This disk is located in front of the strap 34. It 15 is pivotally mounted upon the strap, as by means of the tubular rivet 39. Obviously a greater number of disks than four might be provided, in which case one additional disk (not shown) might be mounted upon the 20 strap 34 and located in rear of the same. A still greater number of disks might be employed through the use of a greater number of straps.

In the construction illustrated in Figs. 25 4, 5 and 6, as in the construction illustrated in Figs. 1, 2 and 3, any one of the characters of the matter appearing through the sight

opening 13 or 12 may be changed independently of the others. For this purpose it is simply necessary to rotate the corresponding 30 disk through a sufficient distance to display the desired character through the opening. Obviously the members 28, and 33, 34 serve as stays for stiffening the display card upon 35 which they are mounted.

I claim as my invention—

In a changeable sign in combination, a display card, a pair of overlapping non-concentric pivoted members located in rear of the card and so arranged as to each display a portion of its surface from the front of the card, and a stay extending over the back of the card between the said pivoted members, and having its opposite ends secured to the display card beyond the margins of that one of the said pivoted members which is located between it and the card, the said pivoted members being mounted upon opposite sides of the stay.

ERNEST J. BURGQUIST.
